INVENTOR

Paul H. Smith,
BY
Finckel & Finckel,
ATTORNEY

UNITED STATES PATENT OFFICE.

PAUL H. SMITH, OF COLUMBUS, OHIO.

TRUNK.

SPECIFICATION forming part of Letters Patent No. 605,143, dated June 7, 1898.

Application filed December 16, 1897. Serial No. 662,194. (No model.)

To all whom it may concern:

Be it known that I, PAUL H. SMITH, a citizen of the United States, residing at Columbus, in the county of Franklin and State of Ohio, have invented certain new and useful Improvements in Trunks; and I do hereby declare the following to be a full, clear, and exact description of the invention, such as will enable others skilled in the art to which it appertains to make and use the same.

I have found by experience that the tube for containing the tray-spindle in such a trunk as is illustrated in my application for patent filed April 2, 1897, Serial No. 630,400, when open at the back and slit in front is rather weak and liable to be bent and distorted.

The object of my present invention is to provide a tube for the tray-spindle that shall be strong and durable and not liable to be bent or broken, however great a strain to which it may be subjected, in the ordinary use of such trunks.

My invention consists in the improved construction of tray-spindle tube hereinafter described and claimed.

In the annexed drawings, Figure 1 is a perspective view of the end of a trunk containing my improved tray-spindle tube. Fig. 2 is a central vertical sectional view of the tube alone, and Fig. 3 is a top plan view.

Like characters of reference in the different views designate corresponding parts.

1 designates the tubular part of the device, in which the tray-spindle is placed and turns. 35 At the rear side of the tubular part and formed integral therewith is a pulley-chamber con-

sisting of parallel walls 2 and a connecting-wall 3. The tubular part 1 and the pulley-chamber communicate through an opening in the tube extending the entire length of the 40 pulley-chamber; but the part of the tube extending beyond the upper end of the pulley-chamber is made solid and preferably thicker than the main portion of the tube, as shown at 1^a, because of the greater strain to which 45 this part is subjected. The parallel walls of the pulley-chamber are made with bearings for the pulleys, over which the tray-elevating cord passes, and the rear edge of the pulley-chamber is provided with ears, by means of 50 which the device is fastened to the end wall of the trunk. The lower edge of the tubular portion is made with an opening, through which the cord passes to the opposite end of the trunk.

55

What I claim, and desire to secure by Letters Patent, is—

In a trunk, a device for containing a tray-supporting spindle, consisting of a tubular portion 1 having a notch or opening at its 60 lower edge and a pulley-chamber having walls 2, 2 and connecting-wall 3 communicating with said tubular portion, the said tubular portion having solid prolongations 1^a of said tubular portion 1, substantially as shown and 65 described.

In witness whereof I have hereunto set my hand this 7th day of December, 1897.

PAUL H. SMITH.

Witnesses:

G. W. ALFRED,
GEO. M. FINCKEL.
